HEATING ELEMENT SUPPORT UNIT FOR OVENS AND THE LIKE

Leonard E. Butters, Albion, Mich., assignor to Union Steel Products Company, Albion, Mich.

Application August 3, 1940, Serial No. 350,535

2 Claims. (Cl. 219—19)

This invention relates to improvements in heating element support units for ovens and the like.

The main objects of my invention are:

First, to provide a heating element support unit for ovens and the like, in which the support unit may be completely assembled and the heating unit easily and quickly mounted thereon.

Second, to provide a heating unit in which the heating element is effectively supported and insulated from its support.

Third, to provide a unit of the type described which is of wire construction throughout, which enables the heating unit and insulators to be readily installed thereon, effecting a considerable economy of labor and time in this operation.

Fourth, to provide a unit of the type described having a minimum of metal surrounding the heating units whereby to increase the efficiency and speed of heating thereof.

Further objects relating to details and economies of my invention will appear from the description to follow. The invention is defined in the claims.

A structure embodying the features of my invention is illustrated in the accompanying drawings, in which:

Fig. 1 is a top plan view illustrating one embodiment of the unit of my invention having a number of insulators assembled thereon, the heating element being indicated in dotted lines.

Fig. 2 is a fragmentary view in section on line 2—2 of Fig. 1, further illustrating certain of the parts of the unit of my invention and their relation to insulators operatively associated therewith.

Fig. 3 is an enlarged fragmentary view in section on line 3—3 of Fig. 1, still further illustrating details of the unit construction and the method of securing the insulators thereto, the position of the insulator clamping means prior to insertion of the insulators being illustrated in dotted lines.

Fig. 4 is a top plan view of a heating element supporting unit in accordance with a modified embodiment of my invention.

Figs. 5 and 6 are enlarged fragmentary views in section on lines 5—5 and 6—6 respectively of Fig. 4.

Fig. 7 is a fragmentary top plan view illustrating a support unit in accordance with a still further modified embodiment of my invention.

Fig. 8 is an enlarged fragmentary view in section on line 8—8 of Fig. 7.

The present invention relates in general to a heating element support for the conventional

household electric oven. More particularly, the invention relates to such a support wherein the amount of metal surrounding or adjacent the heating element is reduced to a minimum, thereby increasing the efficiency and speed of operation of the element. This frame in all the embodiments to be hereinafter described is characterized by the simplicity and ruggedness of the same and by the ease and speed in which the heating element insulators may be associated therewith and the element threaded through the insulators.

Referring to the drawings, in Figs. 1, 2, and 3 I illustrate a heating element support or unit embodying my invention, which comprises a rectangular frame 1 formed of a length of relatively round wire stock, of suitable diameter to provide substantial rigidity, the rear corners 2 of which are substantially rounded to facilitate insertion and removal thereof in the oven of an electric range, for example. This length of stock terminates at the front of the frame at points 3, but is connected between these points in a rigid manner by the elongated depending loop 4 which furnishes a finger piece or handle for withdrawing the unit when desired.

A plurality of spaced cross straps or rods 5 extend laterally across the frame, being welded at their ends 6 to the top of the frame for support thereby. A longitudinal intermediate bracing rod 7 extends from front to rear of the frame, being butt welded at 8 to the rear reach 9 thereof and welded at 10 beneath the foremost cross strap 5. If desired, rod 7 may be curved upwardly over the strap 5 immediately behind the front strap, as indicated at 11, whereby the rod is supported adjacent its front end.

A semi-circular support member 12 is welded on the top of the rear frame reach 9 and the rearmost longitudinal rod 7, this support being preferably of steel strap stock of flat rectangular section and serving, when the unit is completely assembled, to support an electrical connector (not shown) with which the heating terminals of the heating element 13 are secured. This connector coacts with a suitable socket member or connector disposed in the rear of the oven in accordance with conventional practice.

The cross pieces or strips 5 are preferably of flat rectangular section steel rod or wire stock, though it will be appreciated that they might well be of circular stock or other desired outline. Each of said straps has a plurality of insulator gripping clamping elements 15 welded thereto at 16, the construction and arrangement of these

elements relative to the straps being clearly illustrated in Fig. 3. Each consists of a section or element of stock preferably similar to that of which the straps are fabricated, the ends of these elements being offset downwardly and bent into semi-circular configuration at 17. Initially and prior to assembly of the insulators 18 therewith, the curved ends 17 are disposed in the position indicated in dotted lines in Fig. 3. The cross straps 5 are themselves provided with upward bends or curved portions 19 adjacent the point of securement of elements 15 thereto and in position to coact with the curved ends 17 in receiving and clamping the insulators 18 therebetween.

There are a plurality of clamping or securing elements 15 in laterally spaced relation on and parallel to each of the cross rods or straps. In assembling the heating element, all that is necessary is to insert the insulators 18 (which are of annular form and provided with an annular groove 20 on their outer peripheral surface to receive the strap 5 and curved ends 17) into the insulator receiving space described above, and then close up the curved end 17 to bring the same from the dotted line to the solid line position of Fig. 3. This effectively clamps the insulators in place with a minimum of time and trouble. Thereafter, all that is necessary is to thread the heating element 13 through the insulators in the desired manner. In this connection, it will be observed that I provide a pair of auxiliary straps 21 adjacent the rear of the frame and extending between and spot welded to the rear reach 9 and the rearmost cross strap for the reception of further insulators, whereby the heating element is adequately supported adjacent its connection to the electrical connector (not shown).

The foregoing construction is inexpensive, economical, both in its structural aspects and in the ease and quickness with which the heating unit may be assembled. It has a minimum of metal adjacent and surrounding the heating element, so that the thermal efficiency thereof is unimpaired.

In Figs. 4, 5, and 6, I illustrate a modified embodiment of my invention, wherein the border frame 22 is endless and is provided with a pair of parallel side supporting reaches 23 of wire rod stock adjacent and below its side reaches. These auxiliary reaches have spot welded thereto at 24 the upturned ends 25 of a plurality of longitudinally spaced laterally extending cross rods or pieces 26 of any desired section round wire rod stock being used in the embodiment illustrated. These cross pieces 26 have welded to the upper side thereof at 27 the laterally spaced bendable insulator clamping and securing elements 28 which per se are generally similar to the elements 15 illustrated in Figs. 1, 2, and 3, and which coact with the cross pieces 26 in receiving insulators 18 in substantially the same manner.

The cross pieces 26 have welded to the bottom sides thereof a U-shaped wire rod support member 30, the extremities of the legs of which U-shaped member are bent upwards at 31 and welded to the front reach 32 of frame 22 to brace the same. The said leg extremities are also spot welded to an auxiliary U-shaped wire rod member 33 the ends of which extend around the sides of the strap structure supported by the frame and are welded to the upturned legs 25 of the cross pieces in the manner clearly illustrated in Fig. 5. U-shaped support 30 at its

rear end or bight 36 is provided with a sheet metal plate 38 adapted to receive an electrical connector (not shown), it being understood that the bight 36 is spaced substantially below the rear reach of frame 22 by reason of its connection beneath the downwardly offset cross pieces 28.

A supplemental insulator 37 is supported transversely of the other insulators adjacent the front of the frame in a manner similar to that in which the other insulators are supported, i. e., by a section of strap material 371 welded to the foremost cross piece 26 and provided with a bendable clamp 372 at its end (see Fig. 6).

The assembly of the heating element 13 of the foregoing support unit is identical to that described in connection with the embodiment of Figs. 1, 2, and 3 and similar advantages are obtained. The side reaches of frame 22 serve as lateral supports on which the unit may be slid into place in an oven. The whole heating unit is disposed below said reaches and protected by the frame against damage from inadvertent dropping or the like.

In Figs. 7 and 8, I illustrate a still further embodiment of my invention, wherein the endless frame 38 has a plurality of cross members disposed thereon in laterally spaced parallel relation, some of which, indicated by the reference numeral 39, are of the full length of the frame and are welded at their opposite ends thereto, and others of which, indicated by the reference numeral 40, are of only partial length and are welded at one end of the frame and free at their other. This leaves an open space interiorly of the elements 39, 40. Each of the cross members 39, 40 has a plurality of wire insulator supporting and clamping clips 41 welded to its lower surface and extending at right angles thereto. These elements 41 are similar to those of the preceding embodiments and when secured in operative relation and provided with annular insulators in the manner described above furnish a multiplicity of heating element supports arranged in an open-center, box-like relation. The heating element may be arranged to stretch across the space interiorly of the supports, thereby furnishing a large area in which all of the heat evolved by the element is immediately available for broiling or baking purpose.

It will be noted that in Figs. 7 and 8 the clamping elements 41 extend transversely of cross members 39, 40 rather than parallel thereto as in the embodiments of Figs. 1 to 6. For this reason, the curved ends 42 of the elements are made of sufficient length to support the insulators 18 in their entirety and without any further coacting means such as is provided by the cross pieces in the embodiments of Figs. 1 to 6.

The foregoing units are all well adapted for use as broiler or baking units in the conventional electric range and are all characterized by a minimum of metal adjacent and surrounding the heating element, whereby its efficiency is improved. All are strong and sturdy and resistant to damage or displacement of the heating element and in all thereof the heating element and insulators therefor are assembled on the support with speed and facility.

I have illustrated and described my improvements in embodiments which are very practical. I have not attempted to illustrate or describe other embodiments or adaptations as it is believed that this disclosure will enable those skilled

in the art to embody or adapt my improvements as may be desired.

Having thus described my invention, what I claim as new and desire to secure by Letters Patent is:

1. A heating unit for an electric oven, comprising an open frame of rod stock having a plurality of cross straps extending transversely thereof and welded at their ends to the side reaches of the frame, and a plurality of sets of insulator receiving and clamping clips spaced laterally on and welded to said straps, said clips each comprising a pair of curved initially open ends and an integral connecting reach therefor secured to the strap, said ends receiving insulators and being bendable to a relatively closed position upon insertion of an insulator therein to clamp the same in place and said straps having coacting bent portions receiving the insulator when so assembled, whereby the insulators are 20

securely held in position with a minimum of metal surrounding and adjacent the same.

2. A heating unit for an electric oven, comprising an open frame of rod stock having a plurality of straps welded at their ends to the parallel reaches of the frame, and a plurality of sets of insulator receiving and clamping clips spaced along and welded to said straps, said clips each comprising a pair of curved initially open ends and an integral connecting reach therefor secured to the strap, said ends receiving insulators and being bendable to a relatively closed position upon insertion of an insulator therein to clamp the same in place and said straps coacting with said clips in engaging the sides of the insulator, whereby the insulators are securely held in position with a minimum of metal surrounding and adjacent the same.

LEONARD E. BUTTERS.
